WINDOW SASH

Richard N. Anderson, Owensboro, Ky., assignor to V. E. Anderson Mfg. Co., Owensboro, Ky., a corporation of Kentucky

Filed Oct. 16, 1967, Ser. No. 9,008

Term of patent 14 years

(Cl. D13—1)

FIG.1

FIG.2

FIG.3

FIG.4

FIG.5

FIGURE 1 is a perspective view of a window sash showing the outside, one end and one side of my new design.

FIGURE 2 is a perspective view of my window sash showing the inside, other end and other side thereof.

FIGURE 3 is an enlarged cross section view of my window sash taken substantially on the line 3—3 in FIGURE 1.

FIGURE 4 is an enlarged cross section view of my window sash taken substantially on the line 4—4 in FIGURE 1.

FIGURE 5 is an enlarged cross section view of my window sash taken substantially on the line 5—5 in FIGURE 1.

The jambs of my window sash are mirror images of each other.

I claim:

The ornamental design for a window sash, substantially as shown and described.
